(57) **ABSTRACT**

A personal hygiene product disposal apparatus for sealing personal hygiene products in a sanitary manner includes a housing having a housing inside. A plurality of doors is coupled to the housing and comprises a first door coupled to a first aperture extending through the housing front side, a second door coupled to a second aperture extending through the housing front side, and a third door coupled to a third aperture extending through the housing front side. A bag dispenser is coupled within the housing inside adjacent the first aperture. The bag dispenser has a waste bag accessible through the bag slot and is configured to receive a personal hygiene product. A bag sealer is coupled within the housing inside adjacent the second aperture. A cutter is coupled within the housing inside adjacent the third aperture. The cutter separates the sealed portion of the waste bag for removal from the apparatus.

BACKGROUND OF THE INVENTION

(1) Field of the Invention

The disclosure relates to disposal devices and more particularly pertains to a new disposal device for sealing personal hygiene products in a sanitary manner.

(2) Description of Related Art Including Information Disclosed Under 37 CFR 1.97 and 1.98

The prior art relates to disposal devices.

BRIEF SUMMARY OF THE INVENTION

An embodiment of the disclosure meets the needs presented above by generally comprising a housing having a housing front side separated from a housing back side, a housing top side separated from a housing bottom side, and a housing left side separated from a housing right side defining a housing inside. A plurality of doors is coupled to the housing. The plurality of doors comprises a first door coupled to the housing and being pivotably coupled to a first aperture extending through the housing front side. A second door is coupled to the housing. The second door is pivotably coupled to a second aperture extending through the housing front side below the first aperture. A third door is coupled to the housing. The third door is pivotably coupled to a third aperture extending through the housing front side below the second aperture. A bag dispenser is coupled within the housing inside adjacent the first aperture. The bag dispenser has a dispenser front wall lying coplanar with the housing front side and a bag slot extending through the front wall. The bag dispenser has a waste bag accessible through the bag slot and is configured to receive a personal hygiene

2

product. A bag sealer is coupled within the housing inside adjacent the second aperture. The bag sealer has a heating element to form a sealed portion of the waste bag. A cutter is coupled within the housing inside adjacent the third aperture. The cutter separates the sealed portion of the waste bag for removal from the apparatus.

There has thus been outlined, rather broadly, the more important features of the disclosure in order that the detailed description thereof that follows may be better understood, and in order that the present contribution to the art may be better appreciated. There are additional features of the disclosure that will be described hereinafter and which will form the subject matter of the claims appended hereto.

The objects of the disclosure, along with the various features of novelty which characterize the disclosure, are pointed out with particularity in the claims annexed to and forming a part of this disclosure.

20 BRIEF DESCRIPTION OF SEVERAL VIEWS OF THE DRAWING(S)

The disclosure will be better understood and objects other than those set forth above will become apparent when consideration is given to the following detailed description 25 thereof. Such description makes reference to the annexed drawings wherein:

FIG. 1 is an isometric view of a personal hygiene product disclosure according to an embodiment of the disclosure.

FIG. 2 is an isometric view of an embodiment of the disclosure.

FIG. 3 is an isometric view of an embodiment of the disclosure.

FIG. 4 is an isometric view of an embodiment of the disclosure.

FIG. 5 is a cross-sectional view of an embodiment of the disclosure.

FIG. 6 is a cross-sectional view along the line 6-6 of FIG. 2 of an embodiment of the disclosure.

FIG. 7 is a cross-sectional view along the line 7-7 of FIG. 6 of an embodiment of the disclosure.

FIG. 8 is a cross-sectional view along the line 8-8 of FIG. 2 of an embodiment of the disclosure.

FIG. 9 is a cross-sectional view along the line 9-9 of FIG. 45 8 of an embodiment of the disclosure.

DETAILED DESCRIPTION OF THE INVENTION

50 With reference now to the drawings, and in particular to FIGS. 1 through 9 thereof, a new disposal device embodying the principles and concepts of an embodiment of the disclosure and generally designated by the reference numeral 10 will be described.

55 As best illustrated in FIGS. 1 through 9, the personal hygiene product disposal apparatus 10 generally comprises a housing 12 having a housing front side 14 separated from a housing back side 16, a housing top side 18 separated from a housing bottom side 20, and a housing left side 22 separated from a housing right side 24 defining a housing inside 26. A plurality of feet 28 is coupled to the housing bottom side 20. Each foot 28 may be a slider foot to more easily move the apparatus 10. A plurality of doors 30 is coupled to the housing 12 and comprises a first door 32 coupled to the housing 12 and

60 comprises a first door 32 coupled to a first aperture 34 extending through the housing front side 14. The first door 32 is pivotably coupled to a first aperture 34 extending through the housing front side 14. A second door 36 is coupled to the housing 12.

65

The second door **36** is pivotably coupled to a second aperture **38** extending through the housing front side **14** below the first aperture **34**. A third door **40** is coupled to the housing **12**. The third door **40** is pivotably coupled to a third aperture **42** extending through the housing front side **14** below the second aperture **38**. Each door **30** has a spherical knob **44** and a decorative element **45** to turn the apparatus **10** into an aesthetically pleasing piece of furniture.

A storage drawer **46** is slidably coupled through a drawer aperture **48** of the housing front side **14** above the first aperture **34**. A bag dispenser **50** is coupled within the housing inside **26** adjacent the first aperture **34**. The bag dispenser **50** has a dispenser front wall **52** lying coplanar with the housing front side **14**. The front wall **52** has an octagonal frame **54**, a flexible membrane **56** coupled within the frame **54**, and a bag slot **58** extending through the front wall **52**. The bag slot **58** may have a horizontal portion **57** and a pair of V-shaped portions **59**. The bag dispenser **50** has an angled bag frame **60** securing a waste bag **62**. The waste bag **62** is accessible through the bag slot **58** and is configured to receive a personal hygiene product. The angled bag frame **60** aids the user in pushing the personal hygiene product down to extend the waste bag **62**.

A bag sealer **66** is coupled within the housing inside **26** adjacent the second aperture **38**. The bag sealer **66** has a 25 guide track **68** coupled to the housing left side **22** and the housing right side **24** and a push bar **69** slidably coupled to the guide track **68**. A rear bar **70** is coupled to the housing back side **16** and a heating element **72** is coupled to the rear bar **70**. The push bar **69** has a contact pad **74** to activate the heating element **72** when being pushed from a rest position **76** proximal the housing front side **14** to a seal position **78** contacting the rear bar **70**. The heating element **72** forms a sealed portion of the waste bag **62**. The guide track **68** has a spring **80** to automatically return the push bar **69** to the rest 35 position **76**.

A cutter **82** is coupled within the housing inside **26** adjacent the third aperture **42**. The cutter **82** has a pivotable security bar **84**, a cutter track **86**, and a blade **88** slidably coupled to the cutter track **86**. The security bar **84** selectively 40 secures the waste bag **62** to the cutter track **86** and the blade **88** separates the sealed portion of the waste bag **62** for removal from the apparatus **10**.

In use, the user opens the first door **32** and inserts the personal hygiene product through the bag slot **58** of the 45 dispenser front wall **52**. The personal hygiene product falls into the waste bag **62** of the bag dispenser **50**. The angled bag frame **60** aids the user in pushing the personal hygiene product down to extend the waste bag **62**. The user opens the second door **36** to access the bag sealer **66**. The push bar **69** is pressed to engage the heating element **72** and seal the waste bag **62**. The user then opens the third door **40** to access the cutter **82**. The security bar **84** is used to secure the waste bag **62** and the blade **88** is slid along the cutter track **86** to separate the waste bag for removal from the apparatus **10**.

With respect to the above description then, it is to be realized that the optimum dimensional relationships for the parts of an embodiment enabled by the disclosure, to include variations in size, materials, shape, form, function and manner of operation, assembly and use, are deemed readily apparent and obvious to one skilled in the art, and all equivalent relationships to those illustrated in the drawings and described in the specification are intended to be encompassed by an embodiment of the disclosure.

Therefore, the foregoing is considered as illustrative only of the principles of the disclosure. Further, since numerous modifications and changes will readily occur to those skilled

in the art, it is not desired to limit the disclosure to the exact construction and operation shown and described, and accordingly, all suitable modifications and equivalents may be resorted to, falling within the scope of the disclosure. In 5 this patent document, the word "comprising" is used in its non-limiting sense to mean that items following the word are included, but items not specifically mentioned are not excluded. A reference to an element by the indefinite article "a" does not exclude the possibility that more than one of the 10 element is present, unless the context clearly requires that there be only one of the elements.

I claim:

1. A personal hygiene product disposal apparatus comprising:

a housing, the housing having a housing front side separated from a housing back side, a housing top side separated from a housing bottom side, and a housing left side separated from a housing right side defining a housing inside;

a plurality of doors coupled to the housing, the plurality of doors comprising:

a first door coupled to the housing, the first door being pivotably coupled to a first aperture extending through the housing front side;

a second door coupled to the housing, the second door being pivotably coupled to a second aperture extending through the housing front side below the first aperture; and

a third door coupled to the housing, the third door being pivotably coupled to a third aperture extending through the housing front side below the second aperture;

a bag dispenser coupled to the housing, the bag dispenser being coupled within the housing inside adjacent the first aperture, the bag dispenser having a dispenser front wall lying coplanar with the housing front side and a bag slot extending through the front wall, the bag dispenser having a waste bag accessible through the bag slot and configured to receive a personal hygiene product;

a bag sealer coupled to the housing, the bag sealer being coupled within the housing inside adjacent the second aperture, the bag sealer having a heating element to form a sealed portion of the waste bag; and

a cutter coupled to the housing, the cutter being coupled within the housing inside adjacent the third aperture, the cutter separating the sealed portion of the waste bag for removal from the apparatus.

2. The personal hygiene product disposal apparatus of 50 claim 1 further comprising a storage drawer coupled to the housing, the storage drawer being slidably coupled through a drawer aperture of the housing front side above the first aperture.

3. The personal hygiene product disposal apparatus of 55 claim 1 further comprising the front wall of the dispenser having an octagonal frame and a flexible membrane coupled within the frame, the bag slot extending through the membrane.

4. The personal hygiene product disposal apparatus of 60 claim 1 further comprising the bag dispenser having an angled bag frame securing the waste bag.

5. The personal hygiene product disposal apparatus of 65 claim 1 further comprising the bag sealer having a guide track coupled to the housing left side and the housing right side and a push bar slidably coupled to the guide track, a rear bar is coupled to the housing back side and the heating element is coupled to the rear bar, the push bar having a

5

contact pad to activate the heating element when being pushed from a rest position proximal the housing front side to a seal position contacting the rear bar.

6. The personal hygiene product disposal apparatus of claim **5** further comprising the guide track having a spring ⁵ to automatically return the push bar to the rest position.

7. The personal hygiene product disposal apparatus of claim **1** further comprising the cutter having a pivotable security bar, a cutter track, and a blade slidably coupled to the cutter track, the security bar selectively securing the waste bag to the cutter track and the blade separating the sealed portion. ¹⁰

8. The personal hygiene product disposal apparatus of claim **1** further comprising a plurality of feet coupled to the housing bottom side. ¹⁵

9. The personal hygiene product disposal apparatus of claim **1** further comprising each door having a spherical knob and a decorative element. ¹⁵

10. A personal hygiene product disposal apparatus comprising:

a housing, the housing having a housing front side separated from a housing back side, a housing top side

separated from a housing bottom side, and a housing left side separated from a housing right side defining a housing inside; ²⁰

a plurality of feet coupled to the housing bottom side; ²⁵

a plurality of doors coupled to the housing, the plurality of doors comprising:

a first door coupled to the housing, the first door being pivotably coupled to a first aperture extending through the housing front side; ³⁰

a second door coupled to the housing, the second door being pivotably coupled to a second aperture extending through the housing front side below the first aperture; and

a third door coupled to the housing, the third door being pivotably coupled to a third aperture extending through the housing front side below the second aperture; ³⁵

6

each door having a spherical knob and a decorative element;

a storage drawer coupled to the housing, the storage drawer being slidably coupled through a drawer aperture of the housing front side above the first aperture; a bag dispenser coupled to the housing, the bag dispenser being coupled within the housing inside adjacent the first aperture, the bag dispenser having a dispenser front wall lying coplanar with the housing front side, the front wall having an octagonal frame, a flexible membrane coupled within the frame, and a bag slot extending through the front wall, the bag dispenser having an angled bag frame securing a waste bag, the waste bag being accessible through the bag slot and configured to receive a personal hygiene product; a bag sealer coupled to the housing, the bag sealer being coupled within the housing inside adjacent the second aperture, the bag sealer having a guide track coupled to the housing left side and the housing right side and a push bar slidably coupled to the guide track, a rear bar is coupled to the housing back side and a heating element is coupled to the rear bar, the push bar having a contact pad to activate the heating element when being pushed from a rest position proximal the housing front side to a seal position contacting the rear bar, the heating element forming a sealed portion of the waste bag, the guide track having a spring to automatically return the push bar to the rest position; and a cutter coupled to the housing, the cutter being coupled within the housing inside adjacent the third aperture, the cutter having a pivotable security bar, a cutter track, and a blade slidably coupled to the cutter track, the security bar selectively securing the waste bag to the cutter track and the blade separating the sealed portion of the waste bag for removal from the apparatus.
